UNITED STATES PATENT OFFICE.

SAMUEL M. KASS, OF PHILADELPHIA, PENNSYLVANIA.

GLOBE PLACING AND REMOVING DEVICE FOR BULBS.

Application filed May 5, 1926. Serial No. 106,828.

My invention relates to devices for placing and withdrawing electric light bulbs from sockets located in inaccessible positions.

5 The purpose of my invention is to provide a simple and inexpensive spring bulb clamp holder with a friction device for engaging the end of the bulb.

A further purpose is to anchor spring 10 clamping wires for the bulb by extension wires which carry a friction holder.

A further purpose is to provide spring 15 wire clamps having reversely extending anchoring wires surrounded by a frictional covering such as rubber tubing to engage and to turn the bulb.

A further purpose is to frictionally engage the bulb by the clamping jaws.

Further purposes will appear in the specification and in the claims.

I have preferred to illustrate my invention by one general form only, selecting a form which is simple, practical and inexpensive and which at the same time well illustrates the principles of my invention.

25 Figures 1 and 2 are side elevations, taken at right angles to each other, showing the preferred form of my invention with a lamp bulb outlined within the clamp.

30 Figure 3 is an end elevation of the structure of Figure 1, omitting the bulb.

Figure 4 is a fragmentary section of Figure 1 upon line 4—4, and to enlarged scale.

35 Figure 5 is a perspective view showing the clamp holding a short bulb.

Where ceilings are high and in other places where lamp sockets are difficult of access, a holder or clamp mounted upon a handle or pole must be used to place and 40 withdraw the lamps. My device is intended for this use and is shown as applied to a lamp bulb 6 adapted to be fitted into or withdrawn from the socket 7.

45 My holder 8 comprises primarily clamping jaws 9 and 10 and a flaring frictional engaging portion intended to be pressed against the end of the bulb so as to make it possible to turn the bulb within the socket. The frictional flare and the clamp are arranged simply and conveniently by mounting the frictional surface within a flaring member 11 mounted upon a pole 12 by means of a socket 13. I show a simple and inexpensive means for fastening the clamping members and the friction members to the flaring device, here shown as a funnel

by attaching the clamps to the flaring member at 14, 15, 16 and 17 and extending the ends downwardly into the flaring member, i. e. converging them toward the bottom of the flaring member so as to mount upon them cushions or friction devices 18 for which rubber tubing may conveniently be used. The wires carrying the rubber or the tubing may engage some portion of the interior of the flared body or socket to sustain them from swinging movement when the clamp wires are sprung away from each other to engage a bulb, with the result that the clamps spring about their points of attachment at 14, 15, 16 and 17 to grip the bulb and prevent it from falling out. I need not use the spring clamps to grip the bulb with sufficient pressure to prevent the turning of the bulb whether the clamping portions 19 and 20 of the wires be covered with frictional material as at 21 in Figure 5 or not as in the other figures. Ordinarily my invention can be practiced to better advantage by using the frictional engaging 70 surfaces 18 of the rubber tubing to engage the end of the bulb, giving friction when pressure is exerted against the bulb lengthwise and little friction otherwise. Both can be used.

75 In Figure 5 a rubber band 22 is mounted upon the clamping wires to afford frictional engagement at 22' with a short bulb 6'. Where this is to be used the band can be restricted easily to the part of the clamping wires where it will be most useful by forming bends or kinks 23 in the wire to hold the band.

80 In operation the bulb is pressed longitudinally against the ends 19, 20 of the spring clamps, separating them and allowing the bulb to enter to the position shown in Figures 1, 2 and 4 or Figure 5 where the inner part of the bulb is held and centered by the spring clamps and the outer rounded end of 85 the bulb rests against the rubber tubing 18 or band 22, frictionally engaging it and permitting the bulb to be screwed into place in its socket. The spring clamps can then be withdrawn from about the bulb by longitudinal movement of the holder. For withdrawal the clamps are sprung to place over the bulb by longitudinal pressure upon the holder and the bulb is withdrawn by screwing it out of the socket. It can subsequently 90 be detached from the bulb.

85 In view of my invention and disclosure

variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:-

1. In a device for placing and removing electric light bulbs, a flared shell, spring wires secured to the shell and located along the inside of the shell and extended without the same to form a spring clamp outside of the shell, cushioning means for the bulbs mounted directly upon the spring wires, and supports therefor within the shell.
2. In a device for placing and removing electric light bulbs, a flared shell, spring wires secured to the shell and converged along the inside of the shell and extended

without the same to form a spring clamp outside of the shell and supports therefor within the shell, in combination with tubular friction members upon the supports adapted to engage the end of the bulb.

3. In a device for placing and removing electric light bulbs, a flared shell, adapted for mounting upon the end of the bulb, in combination with spring wire side clamps for the bulb mounted upon the shell and reversely extended inside the shell and friction members mounted upon the inside of the extensions to engage the end of the bulb.

4. In a device for placing and removing electric light bulbs, a funnel having a seat at the rear for a handle, spring wires attached to the flare of the funnel to engage the side of the bulb outside of the funnel and rearwardly extending inside of the funnel and rubber tubes upon the extensions inside adapted to engage with the end of the bulb.

SAMUEL M. KASS.
